ERNST EGER, OF DETROIT, MICHIGAN, ASSIGNOR TO MOEGAN & WRIGHT, A CORPORATION OF MICHIGAN.

MIXING MACHINE.

1,427,272.

Specification of Letters Patent. Patented Aug. 29, 1922.

Application filed May 13, 1921. Serial No. 469,119.

To all whom it may concern:

Be it known that I, ERNST EGER, a citizen of the United States, residing at Detroit, in the county of Wayne and State of Michigan, have invented a new and useful Mixing Machine, of which the following is a full, clear, and exact description.

In the manufacture of rubber articles, mixture of the ingredients forming the 10 pounds employed is essential. Commonly it has been the practice to use mills, machines having cooperating rolls between which the ingredients were squeezed until blended. These require manual supplementing. An 15 operative has to manipulate the plastic sleeve that forms about one of the rolls. And consequently the quality of the mix depends upon the skill of the worker. Necessarily the results obtained vary with the 20 skill of the operatives employed. And the mills are dangerous, not infrequently the operatives are injured.

It has been endeavored to avoid the necessity of using mixing mills by substituting 25 machines that require no attention other than charging and discharging. In general these prior mechanical mixers employed kneading members operating in a closed or substantially closed chamber that acted vari- 30 ously on the batch, sometimes grinding it against the end walls, sometimes mashing it against the side walls of the chamber, and in the latter case with or without a back and forth tossing action. So far, as known how- 35 ever none of the prior mechanical mixing machines have completely and fully met the requirements of the trade. They either fail to yield the requisite homogeneity or, in the case of vulcanizable compounds, heated up 40 to an extent causing partial or complete vul- canization. But whatever may be the reason, their failure to meet requirements is evidenced by the prevalent use of the old mixing mills.

The present invention aims to provide a 45 new and improved type of mixer which will meet the requirements of the rubber trade at least and that will enable batches of stock to be homogeneously, quickly and reliably 50 blended and without heating, and consequent vulcanization, at least to an intolerable extent.

With the specific embodiment of the in- 55 vention illustrated in the drawings in mind, and without intent to limit the scope of the

invention more than is required by the prior art, it consists in a machine having a worm-shaped rotor journalled axially in the opposite ends of a substantially closed cylindrical chamber which is of about the same external 60 diameter as the bladed portion of the rotor at one end and is slightly larger than the rotor at the other end. The pitch of the bladed rotor is preferably varied and made less at one end than at the opposite end 65 adjacent a charging opening.

The invention is illustrated in the accompanying drawings in which:

Fig. 1 is a longitudinal sectional view of 70 one embodiment of the invention;

Figs. 2 and 3 are left and right hand elevations respectively thereof;

Fig. 4 is a transverse section on the line 4—4 Fig. 1, and

Fig. 5 is a detailed longitudinal section of 75 the worm-shaped rotor, showing its hollow construction.

In the drawings, the chamber or container is shown defined by a cylinder 1 and suitably stiffened end frames 2 and 3, which are 80 adapted to rest upon the floor and support the cylinder at a convenient height there- above. The end frame 2, constituting what may be termed for convenience the head of the machine, is hollowed out as indicated at 85 4, and the cylinder is likewise hollowed out as indicated at 5. The jackets thereby af- 90 fforded are adapted to be supplied with a heating or cooling medium such as water or steam through the supply pipe 6 and dis- charge pipe 7, it being understood that com- 95 munication between the hollow spaces 4 and 5 is afforded by suitable ports 8 and 9. Jour- nalled in the end frames 2 and 3 is a shaft 10 having thrust collars 11 and a driving or 100 "bull" gear 12 suitably fixed thereto, the latter being adapted to be driven by pinion 13 and shaft 14. But of course the shaft 10 may be driven in any other convenient manner.

Within the cylinder 1, the shaft 10 has helically coiled about it a blade 15, constituting a worm-shaped rotor, whose pitch and diameter, both, are preferably, but not nec- 105 essarily, decreased towards the head 2 where they are least and approach zero.

In the side wall of the cylinder 1, and preferably at the top, is formed the charging opening 16 which is adapted to be closed by a cap 17 or in any other suitable manner. The 110

cylinder 1, for a length approximating that of the opening 16, is formed internally with a smooth surface as indicated at 17 and the portion of the blade 15 which traverses the same is preferably proportioned to barely clear the walls so that charged material will be scraped clean and fed lengthwise the axis of the rotor. But from the line 18 indicating the end of the smooth surface of the cylinder wall to the head 2, the cylinder is rifled or grooved as indicated at 19 in Fig. 4. The worm-shaped rotor 15 is also preferably stepped as indicated at 20 to there barely clear the ribs 21 separating the grooves 19. But from the step at 20 to the head 2, the bladed portion of the rotor is preferably gradually diminished in pitch and diameter. Preferably, but not necessarily, the rotor 15 is of the hollow construction indicated in Fig. 5 to permit regulating its temperature by a circulated heating or cooling medium such as water that may be conveniently introduced through the tube indicated at 22, whose opening free end 23 adjacent the rear or right hand end of the machine, permits the medium to be circulated the full length of the rotor and exhausted from the outlet 24, the medium being supplied through the intake indicated at 25.

For the discharge of a batch that has been mixed an opening may be provided conveniently, preferably in the head 2, at an angle of about 45° to the vertical as indicated at 26 in Fig. 2, this opening being closed by a plug of any convenient construction.

In operation, the discharge opening 26 being closed, and material having been supplied through the opening 16, the worm-shaped rotor carries the ingredients axially of the cylinder, shredding it, in part at least, against the ribs 21 and progressively working it toward the head of the machine. In the preferred construction illustrated, owing to the gradual diminution of the pitch of the blade, the greatest pressure is developed at the head 2 where the material is most efficaciously mashed or kneaded, it will spread toward the side walls of the cylinder and when it accumulates at the head end 2 in excess of the volume or space available, the material is forced to flow axially in a direction opposite the advance of the blade, either through the clearing space between the blade 15 of the rotor and the side walls of the cylinder 1 or through the grooves 19, if they be used. It works backward in this manner until it reaches a point where the pressure is lower and there it is again brought within the range of action of the blade 15 which of course conducts it again towards the head 2. In this manner, a working or mixing movement in a more or less oval or elliptical path or orbit is secured.

The mixing action is very effective, does

not permit any idling or floating of the material in the mill, and the material is continuously cut or shredded, rolled and tubed.

By suitably shaping the discharge opening 26, the completely mixed batch may be tubed out in any form desired.

While the construction above detailed is especially suitable for mixing vulcanizable batches of rubber, it is not limited to such use, plastics in general being blendable therewith. But the construction is not limited to the preferred construction described, being capable of variation without departing from its principles. More or less of the advantages of the invention may be realized with 80 worm-shaped rotor of uniform pitch. And it is of course immaterial whether the cylinder be enlarged or the blade be reduced in diameter at the end of the mixing chamber where the greatest pressure is developed. 85 And while the rifling or grooving of the cylinder is desirable, some of the advantages of the invention may be realized without the channels 19. The rotor may have two blades coiled oppositely about its axis and of a variable pitch either least at the center, as disclosed in a contemporaneously filed application Serial No. 469,118, or the variable pitch of each of the two oppositely inclined blades may be least adjacent the respective ends of 95 the cylinder. It is to be understood therefore that the invention is broader in scope than the illustrated embodiment and reference should therefore be made to the accompanying claims.

Having thus described my invention what I claim and desire to protect by Letters Patent is:—

1. A machine for mixing plastic materials having in combination, a container, and means movable within the container for working material in a substantial oval orbit lengthwise the container.

2. A machine for mixing plastic materials having in combination an elongated substantially cylindrical chamber, and means movable within the chamber for working material in a substantial oval orbit lengthwise the cylindrical chamber.

3. A machine for mixing plastic materials including in combination, an elongated substantially cylindrical chamber, and a worm-shaped rotor therein for working material in a substantial oval lengthwise the cylindrical chamber until blended.

4. A machine for mixing rubber compositions having in combination a chamber substantially circular in cross-section internally throughout its extent, and a worm-shaped rotor therein, said worm-shaped rotor and chamber being of a diameter more nearly equal at one end of the worm than at the other end thereof so arranged and constructed as to cause the materials to move in a predetermined endless path from one 130

end of the chamber to the other, first adjacent the axis of the rotor, then adjacent the walls of the chamber and so on repeatedly.

5. A machine for mixing plastic materials having in combination a cylindrical chamber provided internally with relatively shallow grooves extending substantially in the direction of its length, and a worm-shaped 10 rotor therein.

6. A machine for mixing plastic materials having in combination a cylindrical chamber provided with lengthwise extending grooves, and a rotor therein having a continuously 15 effective screw-shaped blade of less pitch at one end than at the other end of the rotor.

7. A mixing machine having in combination, a cylindrical chamber, openings for permitting the charging and discharging of 20 material into and from the chamber and a worm-rotor whose axis is coincident with that of the chamber, the worm-rotor having screw-shaped bladed-portions substantially fitting the chamber adjacent a charging 25 opening and being appreciably reduced in diameter toward its opposite end.

8. A mixing machine having in combination, a cylindrical chamber substantially closed in operation, and a worm-shaped 30 rotor therein of diminished pitch and diameter from a point adjacent one of its ends to the other.

9. A mixing machine having in combination, a substantially cylindrical container 35 completely closed at one end at least, and a rotor within said container having a screw-shaped blade of variable pitch least adjacent a closed end of the container, said : rotor and container being proportioned and 40 shaped adjacent the portion of the rotor where the pitch is least to permit flow or movement of the batch in a direction opposite to its advance by the blade.

10. A mixing machine having in combination, a substantially cylindrical container completely closed at one end at least and having adjacent its other end an opening in its side, and a rotor within said container of variable pitch least adjacent the 50 end of the container remote from the opening, said rotor and container being proportioned and shaped at the end remote from the opening to clear the container sufficiently to permit movement of the plastic between it and the rotor and at the other end to loosely fit the container whereby to insure working and blending of the material by continuous axial movement thereof in opposite directions first adjacent the axis of the 55 rotor, and then adjacent the cylindrical container beyond the sweep of the rotor.

11. A mixing machine having in combination, a substantially cylindrical chamber, in combination with, a rotor operable in said 60 chamber, having a blade coiled helically at

least once around its axis and of a substantially zero pitch immediately adjacent one end of the cylinder, the periphery of the blade being spaced from the cylinder in the region of its low pitch to permit flow of the 70 materials adjacent the cylinder in a direction opposite their advance by the screw.

12. A mixing machine having in combination, a chamber internally circular in cross section throughout its length and 75 closed at its opposite ends, in combination with a rotor having a coiled blade of a pitch and length adapted to carry the material and mash it against one end of the cylinder, said chamber and blade being of relative 80 diameter adjacent the end against which the material is carried permitting return flow of the material outside the sweep of the blade and in the opposite direction to its advance whereby orbital working is achieved. 85

13. A mixing machine having in combination, a chamber internally circular in cross section throughout its length and closed at its opposite ends, in combination with a rotor having a coiled blade of a pitch 90 and length adapted to carry the material and mash it against one end of the cylinder, said chamber and blade being of relative 95 diameters adjacent the end against which the material is carried permitting return flow of the material outside the sweep of the blade and in the opposite direction to its advance whereby orbital working is achieved, said circular chamber being provided internally with lengthwise corrugations for co-operating with the rotor to 100 shred the material.

14. A mixing machine having in combination, a substantially closed chamber, a helically bladed rotor therein of a pitch 105 suitable to mash and spread the batch against one end of the chamber, and spaced ribs extending substantially lengthwise the cylinder for shredding the material in co-operation with the rotor, said ribs in adjacent pairs defining grooves permitting the material to flow in a direction opposite that in which it is advanced by the bladed rotor. 110

15. A mixing machine having in combination, a chamber closed in operation at its 115 opposite ends, means whereby the chamber may be charged and emptied, in combination with a rotor having a blade whose pitch is varied and, adjacent one end of the chamber at least, whose inclination is more nearly 120 at right angles than parallel to the axis of the rotor.

16. A mixing machine having in combination, a chamber closed in operation at its 125 opposite ends, means whereby the chamber may be charged and emptied, in combination with a worm-shaped rotor revolvable in said chamber and of such pitch and size relative the chamber as to move the material axially in one direction adjacent the rotor's 130

axis and in the opposite direction adjacent the walls of the chamber.

17. A mixing machine having in combination, a chamber closed in operation at its opposite ends, means whereby the chamber may be charged and emptied, in combination with a worm-shaped rotor revolvable in said chamber and of such pitch and size relative the chamber as to move the material axially in one direction adjacent the rotor's axis and in the opposite direction adjacent the walls of the chamber, and means on the interior of the chamber cooperating with the rotor to shred the material.

18. A mixing machine having in combination, a chamber closed in operation at its opposite ends, means whereby the chamber may be charged and emptied, in combination with a worm-shaped rotor revolvable in said chamber and of a pitch and size relative the chamber for carrying the material axially in one direction adjacent the rotor's axis and in the opposite direction adjacent the walls of the chamber, and means for reducing the temperature developed in the batch during the operation of the machine.

19. A machine for mixing batches of plastic composition having in combination, a container closed at one end and a rotor revolvable therein and provided with a blade for mushrooming the material against the closed end of the container and compelling the material to travel axially of the container in opposite directions within and without respectively the sweep of the blade.

20. A machine for mixing plastic materials having in combination, a container,

and means movable within the container for working material in a substantial oval orbit lengthwise the container, said container being provided with charging and discharging openings through the latter of which the compounded batch may be ejected without stopping the operation of the machine, said discharging opening being provided with a closure device.

21. A machine for mixing plastic materials including in combination, a substantially cylindrical chamber, and a worm-shaped rotor therein for working material in a substantial oval orbit lengthwise the cylindrical chamber until blended, said cylindrical chamber being provided with an outlet and closure therefor in its wall that is opposed to the direction the rotor feeds the material, whereby a blended batch may be discharged by the rotor without necessarily halting the operation of the machine.

22. A machine for mixing batches of plastic composition having in combination, a container closed at one end and a rotor revolvable therein and provided with a blade for mushrooming the material against the closed end of the container and compelling the material to travel axially of the container in opposite directions within and without respectively the sweep of the blade, a portion of the container in its closed end being shiftable to provide an opening through which the mixed batch may be extruded by operation of the rotor.

Signed at Detroit, Mich., this 5th day of May, 1921.

ERNST EGER.
